UNITED STATES PATENT OFFICE.

LEE S. CHADWICK, OF SHAKER HEIGHTS VILLAGE, OHIO, ASSIGNOR TO THE CLEVELAND METAL PRODUCTS COMPANY, OF CLEVELAND, OHIO, A CORPORATION OF OHIO.

THERMOSTATICALLY-CONTROLLED LIQUID-FUEL BURNER.

Application filed February 26, 1921. Serial No. 448,107.

To all whom it may concern:

Be it known that I, LEE S. CHADWICK, a citizen of the United States, residing at Shaker Heights Village, in the county of Cuyahoga and State of Ohio, have invented a certain new and useful Improvement in Thermostatically-Controlled Liquid-Fuel Burners, of which the following is a full, clear, and exact description, reference being had to the accompanying drawings.

This invention relates to a thermostatic control for liquid fuel burners of the class wherein wicks are employed, and its fundamental purpose is to provide means that will operate automatically to lower the wick when the temperature of the flame exceeds a predetermined degree and thus prevent the burner from overheating.

A further object of the invention is to provide, in burners of the class employing wicks and involving wick raising mechanism, thermostatic control means which is interplaced between the wick and wick raising mechanism so that the relation between the wick and said mechanism is automatically varied according to the heat of the flame. This permits the wick to be adjusted at will by means of the wick raising mechanism to produce a flame of the desired height when the burner is first lighted, and insures said adjustment continuing except at times when the heat of the flame exceeds a given degree of temperature.

Another object of the invention is to provide an adjustment through which the thermostatic control means may be made to operate at different degrees of temperature, and through which the relation between the thermostatic elements may be altered to compensate for variations therein.

Further objects are to provide a thermostatically controlled liquid fuel burner that is substantial and durable, comparatively simple of construction, positive of action, that is not likely to get out of order, and is convenient of manipulation and adjustment.

The foregoing objects, and others which will appear from the following description are attained in the embodiments of my invention herein disclosed, reference being had to the accompanying drawings wherein in Fig. 1 is a central vertical section through a burner constructed in accordance with one form of my invention; Fig. 2 is a section on

the line 2—2 of Fig. 1; and Fig. 3 is a view, 55 similar to Fig. 1, of another form of the invention.

While my invention is applicable to liquid fuel burners of various types, I have elected to illustrate it in the present instance in connection with tubular burners wherein cylindrical wicks are used.

Common to the two embodiments illustrated in the drawings are the outer wick tube 1 and the inner wick tube 2 which are connected at their lower ends by an annular wall 3, thereby to enclose a space 4 wherein a tubular or cylindrical wick 5 is contained. The wick is equipped with a carrier 7 which embraces the bottom edge of the wick and extends upwardly along its inner side and has recesses or sockets 9 adjacent its upper end. The upper portion of the inner wick tube 2 is in rather close proximity to the wick, while its lower portion is inset somewhat from the plane of the former portion, through a shoulder 10; so as to provide greater space between the inner wick tube and the wick for the accommodation of fingers 12. These fingers have projections 13 that are engaged within the recesses or sockets 9 of the wick carrier, and the fingers pass upwardly through slots 14 in the shoulder 10 and are then directed downwardly inside the inner wick tube. It will be seen that, through this arrangement, the wick may be raised and lowered by means of the fingers 12. I shall presently describe the mechanism for accomplishing this result.

The wick space 4 derives its supply of fuel from a pipe 20 wherewith it has communicative connection through a fitting or elbow 21 that is shown as bound to the pipe by means of a clamp 22. A flame spreader 25 reposes within the upper end of the 95 burner.

Referring now to the form of the invention illustrated in Figs. 1 and 2, 30 is a cylindrical casing that is contracted at its upper end and has connected to it a tube 31 100 which constitutes one of the thermostatic elements. The other element 32 of the thermostat is in the form of a rod and its upper end bears against an abutment 33, represented as a plug that is threaded into the upper 105 end of the tube 31, the lower end of the rod extending into the casing 30. Pivoted upon pins 35, supported within opposed walls of

the casing 30, are a pair of substantially identical levers 36 which are opposed to each other in arrangement and extend through slots 37 in the side walls of the casing, said levers having offset portions 38 extending side by side beneath the rod 32 and whereon said rod bears. The outer ends of the levers 36 are pivotally connected to the lower ends of the aforesaid fingers 12. A comparatively heavy compression spring 40 is shown as interposed between plates 41 and 42, the former plate bearing against the levers 36, and the latter resting upon a pin or abutment 43 which is carried by the casing 30 and is spaced a suitable distance above a second pin or abutment 44 that is also supported by the casing. The spring 40 tends to elevate the levers 36 and hold them in firm contact with the lower end of the rod 32. This unitary thermostatic structure, as I may term it, is mounted for vertical movement with respect to the burner parts, and in the present instance it is shown as guided through a spider 45 that is transversely disposed within the upper end of the inner wick tube and by having the side walls of the casing member 30 slotted, as indicated at 46, to embrace a shaft 50 that is journaled within brackets 51 that depend from the opposite sides of the burner structure. Beyond one of these brackets, the shaft is formed to provide a crank 53. A cam 54 is secured to the shaft 50 within the casing member 30, and is arranged to bear upon the opposed pins or abutments 43 and 44. By means of this cam, when the crank 53 is swung upward and downward, the tubular casing 30, with the thermostatic structure, is raised and lowered, and through its connection with the wick 5, the wick is similarly adjusted.

The thermostatic element represented by the rod 32 which may be of aluminum, has a considerably higher coefficient of expansion than the element represented by the tube 31, which may be of steel.

Assuming then that the wick is lighted and elevated to produce a flame of material height, the heat therefrom, rising about the thermostatic elements, will so affect them that the rod 32 lengthens and depresses the levers 36 against the action of the spring 40, drawing downwardly on the fingers 12 and lowering the wick to reduce the height of the flame. As the temperature of the parts falls, the rod 32 will contract or shorten, allowing the spring 40 to elevate the levers 36 and raise the wick.

In the form of the invention illustrated in Fig. 3, the thermostatic elements are reversed as regards their relative coefficient of expansion. Here a tube 60, which may be of a metal readily effected by changes of temperature constitutes one of the thermostatic elements, and it encloses the other

which is represented by a core 61 of porcelain or the like. The upper and lower ends of the tube 60 are closed by plugs 62 and 63, respectively, and a screw 65 is threaded through the former and has its lower end swiveled to a plate 66 that is secured to the top of the core 61.

Within the tube 60 and below the core 61 are pivotally supported upon pins 68, supported by the tube 60, a pair of levers 69. These levers are also pivotally connected at 70 to ears 71 that depend from a plate 72 attached to the lower end of the core 61. The levers 69 bear, in turn, upon levers 74 that are pivoted at 75 to the tube 60 and their outer ends are connected to the fingers 12. A plate 76 bears against the levers 74, and a compression spring 77 is interposed between said plate and the aforesaid plug 63. A screw 80 has its upper end swiveled within a boss of the plug 63, as shown at 81, and is threaded through the end 82 of a tubular member 83 that is carried by a spider 84 applied to the bottom of the burner structure. The lower end of the tube 60 is guided within the tubular member 83 and thereabove is slidably supported between fins 85 that extend from the inner wick tube.

It will be seen from the above that, by turning the screw 80, the thermostatic structure may be raised and lowered to similarly affect the wick by reason of its connections therewith through the fingers 12. Under excessive heat, the tube 60 elongates, and as it does it swings the outer end of the levers 69 downwardly and a like but exaggerated effect is produced upon the levers 74 because of the engagement of the outer ends of the former levers with the latter levers adjacent their pivotal points. This action of the levers is such as will cause a depression of the wick. This condition will prevail until the tube 60 cools somewhat and contracts and allows the spring 77 to return the levers to their former positions and elevate the wick.

It is apparent from the foregoing that each form of the invention comprises broadly a structure involving a wick guide constituted of the tubes 1 and 2; a wick guided therein; a member (which in the first form is the casing 30 and in the second form the plug 63) supported by the structure and capable of vertical movement; mechanism (in one instance the cam 64 and in the other the screw 80) for so moving the member; a thermostat sustained by the member, and operative connections between the thermostat and the wick.

Having thus described my invention, what I claim is:

1. In a burner of the character set forth, the combination of a supporting structure, a wick carrier adjustable therein, a thermo-

- static structure movably sustained by the supporting structure, means for moving the thermostatic structure, and operative connections between the thermostatic structure 5 and the wick carrier whereby the carrier may be adjusted by moving the thermostatic structure and a variable relation between the carrier and the thermostatic structure may be effected by the heat of the flame.
- 10 2. In a burner of the character set forth, the combination of a supporting structure involving a wick guide, a wick supported therein for vertical adjustment, a member supported by said structure and capable of 15 vertical movement, mechanism for so moving the member, a thermostat sustained by the member, and operative connections between the thermostat and the wick.
3. In a burner of the character set forth, 20 the combination of a supporting structure, a wick carrier mounted therein for vertical movement, a member sustained by the structure for corresponding movement, mechanism supported by the structure for effecting the vertical movement of said member, 25 a thermostat carried by the member, and operative connections between the thermostat and the wick carrier.
4. In a burner of the character set forth, 30 the combination of a supporting structure, a wick carrier guided therein for vertical movement, a member movably supported by the structure, mechanism sustained by the structure for raising and lowering said 35 member, a lever pivotally supported by the member, operative connections between the lever and the wick carrier, and a thermostatic element carried by the member and cooperating with the lever to rock the same 40 upon its pivot when said element is affected by the temperature of the flame.
5. In a burner of the character set forth, the combination with a supporting struc-

ture, a wick guided within the structure for vertical movement, a member movably supported by the structure, mechanism for adjusting said member in a substantially vertical direction with respect to the structure, a lever pivoted to the member, operative connections between the lever and the wick, a 45 thermostatic element carried by the member and serving to swing the lever in one direction when said element is affected by the heat of the flame, and a spring sustained by the member for moving said lever in the opposite direction.

6. In a burner of the character set forth, the combination with a supporting structure, a wick guided for vertical movement therein, a thermostatic couple movably sustained by 60 the structure, means for adjusting the thermostatic couple vertically with respect to the structure, a lever pivoted upon an axis fixed with respect to one element of the thermostatic couple, the other element cooperating 65 with the lever in such manner as to swing it upon its pivot, and operative connections between the lever and the wick.

7. In a burner of the character set forth, 70 in combination with the wick, a manually operable member, operative connections between said member and the wick whereby the wick may be raised and lowered by said member, and thermostatic means for automatically effecting a change of relation between the wick and said member.

8. In a cylindrical oil burner of the wick type, a thermostat extending axially from inside the burner to a point above the same so as to be surrounded by the flame, and 80 means actuated by the thermostat for reducing the size of the flame when the heat of the flame becomes excessive.

In testimony whereof, I hereunto affix my signature.

LEE S. CHADWICK.
